GLADHAND CONSTRUCTION

SUMMARY OF THE INVENTION

A gladhand construction including a housing, a passage therethrough having an inlet and outlet, a valve movable into outlet-closing position in response to separation of the gladhand from engagement with a cooperating construction and in response to fluid pressure entering said inlet, the valve having a portion extending through the outlet for automatic movement of the valve to open position upon engagement with a corresponding gladhand to open the passage. The valve, in preferred form, is a differential piston shuttle wherein the larger piston area is continuously exposed to pressure at said inlet, automatic closure of the valve upon separation of the gladhands serving to seal the outlet, and maintain it sealed, against escape of fluid pressure.

The invention relates to connectors and particularly to gladhand connectors employed in vehicle airbrake systems. Sets of gladhand connectors are carried for example, by the tractor and the trailer of a tractor-trailer combination vehicle. The gladhand connectors are mated, in known manner, by placing one upon the other and rotating them to engage cooperating camming surfaces effective to draw the two connectors into airtight relationship.

One purpose of the invention is to provide a gladhand connector which, upon separation from its mate, provides an automatic seal against the escape of system air from the connector.

Another purpose is to provide a gladhand connector capable of sealing, in its free state, an air pressure system of substantial pressure while permitting the disengagement of such seal and engagement with a cooperating gladhand construction with ease.

Another purpose is to provide a gladhand connector having means automatically sealing the same against loss of air when the connector is disengaged and so constructed as to permit the mating of the same with an identical gladhand connector by minimum manual force.

Another purpose is to provide a gladhand construction which can be mated with an identical construction, each of the mated constructions being effective to seal the system with which it is associated upon separation of said constructions.

Another purpose is to provide an automatically sealed gladhand construction of maximum simplicity and effectiveness.

Other purposes will appear from time to time during the course of the specification and claims.

BRIEF DESCRIPTION OF THE DRAWINGS

The invention is illustrated more or less diagrammatically in the accompanying drawings wherein:

FIG. 1 is a top plan view; and

FIG. 2 is a view in partial cross section and taken on the line 2-2 of FIG. 1.

Like parts are indicated by like numerals throughout the specification and drawings.

DESCRIPTION OF THE PREFERRED EMBODIMENT

Referring now to the drawings, it will be observed that the gladhand construction of the invention includes a housing 1. A deck surface 2 is formed on housing 1. Rising from one end of deck 2 and secured thereto by any suitable means, such as the fasteners 3, is a first camming element 4. Extending from deck 2, forwardly from element 4, is a second camming element 5.

A passage 6 is formed in housing 1 and has an inlet 7 communicating therewith. An outlet 8 extends through deck portion 2 and carries therein the circular seal member 9. Member 9 has an external annular surface 10 surrounding and overlying the outlet 8 and an internal annular surface 11 surrounding and underlying the outlet 8. The seal member 9 has an axial aperture 12 communicating with a chamber 13 with which passage 6 communicates, as indicated at 14.

The chamber 13 is closed at its lower end, as the parts are shown in the drawings, by a bushing or cup element 15, a seal

ring 16 being provided to seal against the escape of fluid pressure from chamber 13. The circumferential inner wall of chamber 13 is provided with lands and grooves intermediate its ends, as indicated at 17. Grooves aligned with passage 6 are open to constitute slots.

Slidable in chamber 13 is a differential piston valve member or shuttle valve 20. A yielding means 21 urges the member 20 toward the seal 9 and outlet passage 12 therein. The member 20 has a first or lower piston portion 22 carrying a seal 23 in continuous engagement with the inner circumferential wall surface of the bushing member 15. A reduced central portion 24 extends between smaller piston portion 22 and the larger-diameter piston portion 25 which in turn carries the circumferential seal 26 in engagement with the inner circumferential wall of chamber 13.

Formed on valve member 20 and extending therefrom through the outlet passage 12 of seal 9 and in circumferentially spaced relationship therewith is a finger or extending portion 27. It will be observed that the portion 27 extends beyond annular external surface 10 of seal member 9 and thus beyond deck surface 2.

Whereas there has been shown and described an operative form of the invention, it should be understood that this showing and description are to be taken in an illustrative or diagrammatic sense only. There are many modifications in and to the invention which will be apparent to those skilled in the art and which will fall within the scope and spirit of the invention.

The use and operation of the invention are as follows:

With the gladhand construction of the invention in its free or disconnected state, as shown in the drawings herein, the fluid pressure of the airbrake system (not shown) communicating with inlet 7 is present in chamber 13 about the reduced portion 24 of valve member 20 and acts against the larger undersurface of piston portion 25 to urge the valve into its closed position as shown. Said pressure, which may be of the order of 100 p.s.i., also acts against the smaller, upper, annular surface, as the parts are shown, of the smaller piston portion 22. The differential in said piston portions, however, in conjunction with the action of relatively light spring 21 retains the valve in the closed position shown.

In addition to the seal provided by ring 26 against the solid upper wall surface of chamber 13, as shown in FIG. 2, the valve member 20 carries an external valve seat configuration 28 which contacts and seals against the annular undersurface 11 of seal member 9, serving as a secondary seal against escape of air from the gladhand construction of the invention, and a safety factor against leakage therefrom, when the gladhand is separated from its mate.

It will be understood that pairs of identical gladhand constructions are conveniently provided in normal use. When the construction of the invention is to be connected with its identical counterpart, the operator places the other gladhand construction onto that shown in the drawings herein. In so doing, the corresponding fingers or extending portions 27 will be brought into contact with each other and the operator will press the housings 1 together thereby moving the valve members 20 in a direction inwardly of the two housings and will engage camming elements 4 and 5 and rotate, relatively, the two gladhands, separating the valve faces 28 from seal surfaces 11 and aligning seals 26 with the lands and grooves 17, thereby providing communication through passages 6, slots and grooves 17 and outlet passages 12.

Since the pressures within the systems are also operating against the smaller piston surfaces of the valve members of the two constructions and the spring 21 is relatively light, it will be realized that the members 20 may be pressed inwardly with ease even though the fluid pressures present in chambers 13 may be of the order of 100 p.s.i. The gladhands are rotated to engage camming elements 4 and 5 and seal surfaces 10 and thus to draw the gladhands into sealed engagement.

When the gladhands are separated, as for example when a trailer is separated from a tractor, the valve members 20 are moved immediately and automatically into closed position.

Spring 21 insures movement of seal 26 toward the solid upper wall of chamber 13 and fluid pressure in passage 6, now beneath the annular undersurface of piston 25, moves valve 20 rapidly into the closed position shown in FIG. 2. Thus it is virtually impossible for the gladhand construction of the invention to result in the loss of any substantial air from the fluid pressure brake systems with which it is associated. The double seal function created by the seal 26 and the contact of valve face 28 with the undersurface 11 of the seal 9 formed of flexible material insures against the loss of air pressure from the gladhand through the outlet passage 12 in the seal 9, while seals 23 and 16 preclude the loss of fluid pressure through or alongside bushing member 15.

We claim:

1. A gladhand construction having an inlet, an outlet and a passage communicating said inlet and outlet, a shuttle valve in said passage, said shuttle valve having a portion extending outwardly through and beyond said outlet, said shuttle valve being in the form of a differential piston member having a first larger piston portion, a second smaller piston portion and a reduced central portion therebetween, a first circumferential seal carried by said first piston portion, a second circumferential seal carried by said second piston portion, said

reduced central portion, piston portions and circumferential seals being exposed to inlet pressure at all positions of said shuttle valve, said larger piston portion and first circumferential seal controlling communication through said passage between said reduced portion and said outlet, said shuttle valve being urged in its free state into a position closing said outlet in response to fluid pressure entering said inlet.

2. The structure of claim 1 characterized by and including an annular seal member carried in said outlet, said valve extending portion extending through said seal member in spaced relationship therewith, said first circumferential seal engaging an inner wall of said construction to seal said outlet when said valve is in an and immediately adjacent its outlet closing position, said larger piston portion carrying an annular valve face 15 end configuration in position to contact said annular seal member to further seal said outlet when said valve is in said outlet closing position.

3. The structure of claim 1 characterized by and including land-and-groove conformations positioned in said passage for 20 alignment with said larger piston portion and said first circumferential seal when said shuttle valve is out of said outlet closing position.
